UNITED STATES PATENT OFFICE.

RAGNAR O. W. LUNDIN, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

1,291,651.

Specification of Letters Patent.

Patented Jan. 14, 1919.

Application filed October 15, 1917. Serial No. 196,586.

To all whom it may concern:

Be it known that I, RAGNAR O. W. LUNDIN, a citizen of the United States of America, residing at New Britain, Connecticut, have invented a new and useful Electric Switch, of which the following is a specification.

My invention relates particularly to switches of the push button type and aims primarily to provide a switch of this character which will be simple, small and compact in construction, which will be quick in its action, which will require a relatively short movement to effect its operation, and which will have a high current-carrying capacity. A special feature of the invention is the construction of the snap switch mechanism in such form that it may be disposed wholly at one end of the switch base to enable the mounting of a supplementary or auxiliary switch, such as a rotary snap switch on the other end of the insulating base.

Briefly, the invention comprises in combination with a supporting frame mounted on the base, a push button slidably mounted in said frame and connected by means of a switch throwing spring with a swinging contact making lever pivoted on the frame at one side of said push button. This sliding push button is connected at its upper end with a rocker, which may have a second push button engaged with its opposite end, and this rocker is preferably pivoted on a post provided by an upstanding part on the supporting frame.

In the accompanying drawings, I have illustrated the invention embodied in the preferred form, but I would have it understood that changes and modifications may be made without departing from the true spirit and scope of the invention.

In said drawing:

Figure 1 is a side view of the switch with the insulating base portion broken away and shown in section to disclose the snap switch mechanism therein.

Fig. 2 is a top plan view of the lower half or main part of the switch base and parts carried thereby.

Fig. 3 is a bottom view of the same to illustrate the several cross connections.

Fig. 4 is a cross sectional view taken substantially on the plane of the line 4-4 of Fig. 2.

55

Fig. 5 is a similar view with the switch parts in a different position.

Fig. 6 is an enlarged detail view of the snap switch mechanism removed from the base, the push button being broken away for lack of space.

Considering the drawing now more in detail, 7 designates the supporting frame set down in a recess 8 in the switch base 9 and made up of base portion 10 with upstanding side parts 11 bent toward each other at their upper ends to form a top portion 12. This frame is shown secured in place by means of screws 13 passed up through the bottom of the insulating base into engagement with the base portion of the frame. Formed in the top and bottom portions of this frame are guide slots 14 and 15 for the sliding stem or shank 16 of the push button 17, the upper guide slot 14 being open at the side of the frame as clearly shown in Fig. 6 and the lower guide slot 15 extending entirely through the base portion of the frame as is also shown in this view.

65

The stem of the push button has a rearwardly bent angled lug 18 which forms an anchorage for one end of the switch throwing spring 19, the opposite end of this spring being connected at 20 to the free end of a contact making lever 21 which is pivoted in the frame at 22. The pivot guides for this lever may be formed as open slots in the side arms 11 of the frame and disposed in the edge of the frame opposite that edge in which the open guide slot 14 is provided. This enables an assemblage of these parts by simply engaging the pivots 22 of the lever sidewise in the pivot slots in one edge of the frame and the dropping of the push button shank in the lower guide opening 15 therefor, the spring 19 serving when connected with these parts to hold them in their open bearings.

70

The throwing spring is connected with the push button slide at a point 23 which

75

upon reciprocation of the slide will travel to opposite sides of the pivotal point 22 of the contact making lever and so cause said lever to quickly snap in one direction or the other as the moving end of the spring is carried past the pivotal center.

The circuit is completed and broken by the contact making lever in the case illustrated by providing it with a contact arm 10 secured to the swinging lever 21 by an insulated joint at 25 and projecting past the pivotal point of the lever and beyond the opposite side of the frame, where it is adapted to form a bridge between a pair of 15 relatively stationary contacts 26-27. The oscillating movement of the contact making lever is limited by stop portions 28 on the opposite edges of the lever, adapted to engage with the top and bottom edge portions 20 of the frame, as clearly shown in Fig. 4, and the reciprocatory movements of the push button may be limited by the upper and lower edge portions of the anchorage lug, engaging the top and bottom of the frame 25 as indicated by Figs. 4, 5 and 6. The push button stem may further be notched as indicated at 29 in Fig. 6 where it engages in the upper open guide slot 14, the ends of such notch also being utilized as stops when 30 so desired.

Another feature of the supporting frame is the provision of it with a laterally offset extended upstanding post 30 for the switch operating rocker 31 which is shown pivoted thereto at a point intermediate its ends at 35 32. This rocker is shown engaged with the upper portion of the push button shank 16 by means of a lug 33 which is hooked into an opening 34 provided for it in the push 40 button shank.

The opposite end of the switch operating rocker is shown engaged with the second push button 35 by means of a fork 36 embracing a flange 37 on the lower end of the 45 push button. This second push button is also indicated as slidably engaged on a spindle 38 which may be the spindle of a rotary snap switch mechanism such as that indicated generally at 39 in Fig. 2.

From this description it will be apparent 50 that as the push buttons are operated the movably supported end of the switch throwing spring is carried past the center of support of the contact making lever which will 55 cause said lever to be alternately snapped in opposite directions, thus quickly making and breaking contact. The shiftable end of the spring need be carried but a slight distance to each side of the pivotal center of 60 the lever, and hence the push button movement necessary for effecting snapping of the switch need only be relatively slight. This push button movement is an advantage in that the buttons need not project so far,

they are easier to operate and the parts can 65 be made smaller and disposed more compactly.

The connection between the two switches are illustrated in a general way in Figs. 2 and 3 wherein 40, 41, 42 and 43 designate 70 the four switch terminals, terminal 40 being connected by the back strap 44 with one of the rotary switch contacts 45, terminal 41 being connected directly with the stationary snap switch contact 26, terminal 42 being 75 connected by a back strap 46 with the rotary snap switch contact 47 and terminal 43 being connected with the rotary switch contact 48.

I claim—

1. In a switch of the character set forth, a switch base, a supporting frame mounted on the base at one end thereof and having an upstanding post disposed substantially centrally of the base, a rocker pivoted on 85 said upstanding post, push buttons connected with the opposite ends of said rocker, one of said push buttons having a dependent stem slidably engaged in the supporting frame, a swinging contact making lever pivoted on the supporting frame at one side of the sliding stem of said push button and a switch throwing spring connected at one 90 end to the free end of the swinging contact making lever and connected at its opposite end to the sliding push button stem at a point which in the reciprocation of such stem travels past the center of pivotal support of the contact making lever.

2. In a switch of the character described, 100 a switch base, a supporting frame mounted on the switch base and comprising a supporting base and upstanding arms rising therefrom, one of said arms having a laterally directed upstanding post and said base 105 portion and arms having guiding slots for a reciprocating slide, a rocker pivoted on the upstanding post, a push button connected with one end of the rocker and having a shank portion slidably guided in the slots 110 in the supporting frame, a contact making lever pivoted in the supporting frame at one side of said stem, a switch throwing spring connected between said stem and the free end of the contact making lever and a 115 push button connected with the opposite end of the rocker.

3. In a switch of the character set forth, a switch base, an open supporting frame mounted in an upright position on said base 120 having a guiding slot extending through the base portion thereof and a guiding slot in the top thereof, open at one side of the frame, a swinging contact making lever pivoted in the opposite side of the frame, an 125 operating slide vertically movable in said guiding slots and a tension spring connected between the operating slide and the free

end of the said contact making lever, said tension spring holding the operating slide engaged in the open guiding slot.

4. In a switch of the character set forth, 5 a switch base, a switch frame mounted thereon and provided with spaced guide slots, an operating slide working in said guide slots and having an angularly turned anchorage lug, a contact making lever piv-

oted on the frame, a switch tension spring 10 connected with the free end of said pivoted lever and with the anchorage lug of the slide, coöperating stop shoulders on the slide and frame limiting the reciprocatory movements of the slide and coöperating stops on 15 the contact making lever and frame limiting the oscillatory movements of said lever.

RAGNAR O. W. LUNDIN.
